APPARATUS FOR DELIVERING AND APPLYING ADHESIVE TAPE OR THE LIKE

George Kenneth Charles, Wincanton, England

Application July 17, 1952, Serial No. 299,456
In Great Britain October 19, 1951

2 Claims. (Cl. 216—21)

1

The invention relates to apparatus for applying pressure-sensitive coated adhesive strip to packages and of the type comprising a pressure roller carried by a pivoted lever so that the roller is normally above a platform, and means for holding a pressure-sensitive adhesive strip in front of the roller so that when a package is propelled by hand along the platform it engages with the strip, forces it against the roller and depresses the roller below the platform, whereby the strip is pressed by the roller on to the package, the strip being severed by contact with a serrated knife as the package completes its travel.

The lever has a return spring to enable it to return the roller to normal position ready for a subsequent operation.

In this known type of apparatus the strip is drawn from a spool during the travel of the package, the strip passing between suitable detent means to the aforesaid roller.

As the layers of strip on the spool tend to stick together, considerable force is required to pull the strip from the spool, and in use of apparatus of the above type it is found that the consequent tension in the strip is such that the strip is frequently pulled off or slips on the package before severance.

With an apparatus of this type, serious difficulties are encountered, namely, the tendency for the strip to be pulled off the package before severance owing to the undue tension in the strip required to pull strip from the spool; the tendency under high tension for the cutter to tear the strip so that a ragged or pronouncedly serrated end is left; the tendency for the strip guide plate to contact with the package after severance and before the package has passed off the pressure roller; and the tendency for the strip guide to bring the protruding strip to the rear instead of the front of the pressure roller on its return to normal position.

The invention consists in an improved apparatus of the type referred to embodying novel features adapted to cooperate so as to avoid the difficulties mentioned above.

In the drawings:

Figure 1 is a side sectional elevation of the apparatus with the parts in normal position, the section being on the line 1—1, Figure 2.

Figures 2 and 3 are front and rear elevations, respectively, the casing being broken away in both figures, and the spool and holder being broken away in Figure 2.

Figure 4 is a side sectional elevation on the line 4—4, Figure 2.

2

Figure 5 is a similar view to Figure 1, but with the parts shown in the position occupied just prior to severance of the strip.

Figures 7 and 8 are side views of the rocking plate and cam plate in different positions.

Figures 6 and 9 are side views of the positions of strip and cutter in different positions.

Figures 10, 11 and 12 are plans of portions of strip.

10 The apparatus illustrated by these drawings, in which similar reference numerals indicate corresponding parts, comprises a package platform 1 having a slot 2 through which a lever 3 protrudes. The platform 1 forms a removable lid for a casing 11. It supports a plate 13 which is screwed to brackets 12, Figures 1, 2 and 3, formed on the underside of the platform 1. The lever 3 supports a pressure roller 5 of rubber, felt or other suitable resilient material, the roller being free to rotate on a stud 6 fixed to the lever 3. The lever 3 in its normal position, Figures 1, 2 and 3, is practically upright. It is fixed on a fulcrum shaft 4 supported in a bearing boss 41, Figure 3, on the plate 13. The upper end of the lever 3 is slightly curved forward so that the stud 6 of the pressure roller is forward relatively to the fulcrum shaft 4 for a purpose hereafter referred to. The lower end of the lever 3 carries a feeding roller 7, preferably having a knurled periphery, the roller 7 being free to rotate on a stud 8.

The lever 3 is held in its normal position against a rubber stop or buffer 40, Figure 1, on the plate 13 by means of a return spring 23, Figures 2, 3 and 4, one end of which is attached to a rocking plate 29 which is fixed to the fulcrum shaft 4, while the other end is attached to an adjusting screw 25 sliding in a hole in a stud 26 under the action of a nut 27.

40 A guide plate 9 for pressure-sensitive adhesive strip 35 protrudes at its upper end through the slot 2 in the platform 1. It is formed integrally with and at right angles to a plate 9' which is fixed to a shaft 10 capable of oscillating in a bearing boss 34, Figure 2, on the plate 13. A detent 14 presses the strip 35 against the guide plate 9. It is mounted to oscillate on a pin 15 fixed to the plate 9' and is held resiliently against the strip 35 by a spring 16, one end of which is attached to the detent and the other end to a lug 17 on the plate 9'.

45 A small lever 18 is secured to the detent 14 and bears on the pin 15. The lever 18 enables the detent 14 to be moved away from the guide plate 9 for a purpose referred to later on.

55 A cam plate 31 situated on the opposite side

of the plate 13 to the guide plate 9, is fixed on the shaft 10, as seen more clearly in Figure 4. A link rod 30 has end pins 30' and 31' formed in the example shown by bending the ends at right angles.

The pin 30' engages in a cam slot 32 in the cam plate 31, and the pin 31' is pivoted in the rocking plate 29. The plates 29 and 31 act as cranks. A spring 33 attached to the plate 31 and to the end 30' of the rod 30 tends to hold the end 30' against the end of the slot 32 as shown in Figure 4, but permits of relative movement of the end 30' in the cam slot 32 for a purpose referred to later.

A spool of pressure-sensitive adhesive strip 35 is mounted on a spool holder 36 which is free to rotate on a bolt 37 on the plate 13.

Guide rollers 38 and 39 on the plates 13 and 9', respectively, are provided for the adhesive strip 35.

A thin steel serrated cutter 19 is screwed at its lower end to a rigid backing plate 21 which is fixed by screws 24 in the slotted end of a stud 20 fixed on the plate 13. The cutter 19, being springy, tends to move away from the backing plate 21, its movement being limited by the head of a screw 22 which passes freely through a hole in the cutter 19.

In preparing the apparatus initially for operation, adhesive strip 35 is drawn by hand from the spool under the guide roller 38 round the knurled roller 7, under the guide roller 39, up the guide plate 9 between the detent 14 and the guide plate, so that the end of the strip projects beyond the upper end of the guide plate and is approximately level with the centre of the pressure roller 5. To facilitate the threading of the strip between the detent 14 and the guide plate 9, the operator depresses the lever 18 which, bearing on the pin 15 as a fulcrum, withdraws the detent.

When a package 41 is propelled along the platform 1, it first engages with the adhesive strip 35 at the upper end of the guide plate 9 and swings the guide plate about its fulcrum pin 10 until the projecting end of the strip is pressed by the package against the pressure roller 5. During this initial movement of the guide plate 9, the cam plate 31 also moves slightly, but the link rod 30 is not moved as its end 30' is free in the cam slot 32.

As soon as the pressure of the package on the pressure roller 5 is sufficient to overcome the resistance of the spring 23, the lever 3 begins to move and rotates its fulcrum shaft 4 and consequently the rocking plate 29. The pressure roller 5 first rises slightly, being forward of a vertical centre line passing through the shaft 4. This initial rising of the pressure roller 5 ensures that the end of the strip 35 is pressed firmly into adherence with the package.

As the package 41 continues its travel on the platform 1, the strip 35 is drawn by it to the cutter 19, as indicated in Figure 5, the guide plate 9 still being free to move under the slight pull of the strip. Immediately the strip 35 is over the cutter 19, the end 30' of the rod 30 engaging with the adjacent end of the cam slot 32, Figure 6, causes a sharp movement of the cam plate 31, so that the guide plate 9 is suddenly depressed to bend the strip over the cutter 19, as indicated in Figure 6. The strip is first perforated neatly by the points of the teeth of the cutter. On further travel of the package and depression of the pressure roller, the strip draws the cutter 19 against the rigid backing plate 21, as indicated in Figure 7, strip to the package completed; and that the

9, so that the perforated strip is drawn down the cutter teeth and neatly cut by them between the perforations. Figure 10 shows a perforated portion of strip and Figure 11 the neatly severed edge as contrasted with the undesirable ragged or pronouncedly serrated edge indicated in Figure 12.

The continued movement of the package and consequently of the lever 3, results in the rocking plate 29, rod 30 and cam plate 31 assuming the positions indicated in Figure 7, so that the guide plate 9 is retained depressed until the package has passed off the pressure roller 5 and the adherence of the severed position of strip to the package has been completed. This retention ensures that the guide plate 9 will not engage with and scrape the underside of the package.

The ends 30', 31' of the link rod 30 in this position may be in alignment with the fulcrum shaft 10, that is on a dead centre, but as the package releases the pressure roller 5 and the return spring 23 begins to return the parts to normal position, the end 30' of the rod 30 rides up the adjacent inclined edge of the cam slot 32, as indicated in Figure 8 so that it is free to slide towards the opposite end of the slot. The return of the guide plate 9 begins immediately as the spring 33 acts as a link between the end of the rod and plate 31. This ensures that the guide plate 9 and its protruding portion of strip shall not be overtaken by the returning pressure roller 5 and that the protruding portion of strip will be arrested in front of and not behind the pressure roller.

During the depression of the pressure roller 5 and the lever 3 by the package 41 as above described, the lever 3 moves the feeding roller 7 towards the spool of strip 35 so that the loop of strip around the feeding roller is left slack. Consequently while the package 41 is drawing strip between the detent 14 and guide plate 9, there is no tension in the strip other than the slight tension required to overcome the friction of the detent and guide plate which is sufficient to ensure proper engagement with the cutter 19 and severance of the strip. Consequently, the tendency to pull the strip off the package hitherto encountered is avoided. The considerable tension required to pull the strip from the spool is effected on the return movement of the lever 3 under the action of the return spring 23 when the feeding roller 7 moving back engages with the strip. When this occurs the detent 14 prevents the strip being pulled down the guide plate 9, as the friction between the strip causes the detent to move towards the guide plate and grip the strip.

As the lever 3 is practically upright in its normal position and the roller 5 is considerably farther from the fulcrum 4 than the connection of the spring 23 to the plate 29 the force required to depress the lever 3 is comparatively light, and crushing of fragile packages is avoided.

It will be appreciated from the foregoing description that owing to the avoidance of undue tension in the adhesive strip during application to a package, slipping of the strip from the package is avoided; and in spite of the light tension the strip is drawn lightly to the cutter, sharply bent or drawn down to enable neat perforation to be effected before actual severance; the guide plate is prevented from scraping the package by being retained depressed until the package has passed over the pressure roller and application of

strip to the package completed; and that the

considerable tension required to draw strip from the spool is effected during the return of the pressure roller and strip guide to normal position.

I claim:

1. An apparatus for applying pressure-sensitive strip to packages of the type hereinbefore referred to, comprising a slotted platform, a lever carrying a pressure roller above said platform, a pivoted guide plate and detent for supporting pressure-adhesive strip in front of said pressure roller for engagement by a package propelled along the platform, a serrated cutter below the platform, for the purpose of severing the strip drawn over it by the package as said package depresses said pressure roller and lever, a return spring for said lever, and a rotary holder for a spool of strip, said lever being mounted on a fulcrum situated intermediate of its ends and being provided with a feeding roller mounted on the opposite end of the lever to that carrying said pressure roller for the purpose of engaging with a loop of strip during the return movement of the lever to draw strip from a spool on said spool holder and leaving said loop slack during the operative movement of said lever.

2. An apparatus for applying pressure-sensitive strip to packages, as specified in claim 1, provided with a rocking plate fixed on the fulcrum shaft of the lever which carries the pressure roller, and a cam plate having a cam slot, said cam plate being fixed on the fulcrum shaft of the strip guide plate, the return spring for the pressure roller lever being attached to said rock-

ing plate, a link rod having one end pivotally attached to said rocking plate and its other end engaging within the cam slot in said cam plate, and a spring connecting said other end to said cam plate, for the purposes of permitting initial movement of said guide plate relatively to the pressure roller under the thrust of a package, effecting sharp depression of the guide plate preparatory to severance of the strip by the cutter; retention of the guide plate in its depressed condition until the package has passed over the pressure roller, and to effect return of the guide plate in advance of the pressure roller during the return thereof to normal position.
